METHOD OF INHIBITING UNDESIRABLE RADIOACTIVE LABELING AND RADIATION DAMAGE IN SYSTEMS CONTAINING MATERIAL UNDERGOING RADIOACTIVE DECAY

Kang Yang and Preston L. Gant, Ponca City, Okla., assignors to Continental Oil Company, Ponca City, Okla., a corporation of Delaware

Filed Mar. 15, 1961, Ser. No. 96,018

7 Claims. (Cl. 252—301.1)

This invention relates to a method for inhibiting undesirable radioactive labeling and radiation damage in systems containing at least one component which emits high energy electrons or gamma photons in undergoing radioactive decay. More particularly, but not by way of limitation, the present invention relates to a method of suppressing the degradation and alteration of molecules resulting from subjecting such molecules to impingement by high energy electrons produced during radioactive decay of radioactive materials. In a more specific aspect, the present invention relates to a method for storing tritium and tritium-labeled compounds so that the formation of undesirable compounds in the system is inhibited.

Compounds labeled with radioactive elements play important roles in the investigation of numerous problems in chemistry and biology. The synthesis of such compounds is frequently quite laborious and time-consuming. After the compounds have been prepared, it is often desired to store them for subsequent experiments. In the past, the storage of such labeled compounds has been very difficult due to the fact that the radioactive tracer atom underwent uncontrollable radioactive disintegration, and the resulting radiation not only damaged the labeled compounds but also produced various undesirable products.

A closely related problem is encountered in the storage and preservation of certain radioactive isotopes. For example, when tritium is stored in glass or steel containers, small amounts of methane contaminate the system over short periods of time, and the radioactive decay of the tritium leads to radioactive labeling of the methane as manifested in the formation of tritiated methane. Even the purest tritium which is commercially available contains tritiated methane in quantities sufficient to give various undesirable side products when the tritium is reacted with organic compounds for the purpose of producing tritium-labeled compounds. The tritiated methane which is present also interferes with mechanism studies of radiolysis reactions initiated with the β decay of tritium. When the impurity is removed from the tritium by laborious and expensive purification techniques, the tritium again becomes contaminated in a relatively short period of time, apparently due to small amounts of organic material in the storage container and not readily removable therefrom.

Whether the system stored be one containing only radioactively-labeled compounds, or radioactively-labeled compounds in the presence of a diluent, or simply radioactive isotopes having traces of organic material present, the formation of undesirable products in the system and the accelerated decomposition of the labeled compounds originates in the uncontrollable radioactive decay or disintegration of the radioactive atoms in the system. We have studied the reaction mechanism of this radioactive disintegration and the manner in which the decay products influence the formation of undesirable compounds or accelerate the decomposition of the labeled compounds initially present in the system. These studies have led to the discovery that the formation of free radicals is an important step in the process of such formation and accelerated decomposition, and the present invention is bottomed upon this discovery.

2

It is known that undesirable free radical reactions may be inhibited by the addition of certain radical-scavenging compounds to a system containing free radical-producing materials and materials which are attacked by, or will react with, such free radicals. The present invention can therefore be said to reside in the discovery that free radicals are produced in certain systems containing radioactive elements and that the undesirable effects of subsequent reactions of these radicals with compounds or other radicals present in the system can be inhibited by the introduction of certain compounds to the system which will react with the radicals to form stable compounds not readily undergoing subsequent decomposition or further reaction. The selection of the type of radical-scavenger employed is dependent upon the compounds of the system which are to be protected, while the amount or quantity of scavenger to be added is dependent upon the period of storage.

Accordingly, it is a major object of the present invention to provide a method for inhibiting radiation damage in a system containing at least one compound which undergoes spontaneous radioactive decay.

It is a further object of the present invention to provide a method for inhibiting the formation of undesirable products resulting from radioactive decay in a system containing a radioactive isotope and small quantities of organic material.

It is another object of the present invention to provide a method for inhibiting radiation damage to chemical compounds labeled with radioactive tracer atoms and to unlabeled organic compounds used as diluents in storing such labeled compounds. The invention also has as its object the inhibition of the formation of undesirable products in systems which include such labeled compounds and diluents.

The manner in which the cited objects are achieved will be better understood upon reading the following disclosure, whereupon additional objects not hereinbefore described will become manifest.

The sole accompanying drawing is a typical curve in which the tritiated methane/tritium ratio of the system is plotted against time and illustrates the manner in which purified tritium gas is rapidly contaminated with tritiated methane when purified tritium is merely allowed to stand in a Pyrex storage bulb.

In early studies of radioactive materials, it was observed that β rays, soon recognized as very energetic electrons, were emitted spontaneously by a large number of radioactive materials. The positively charged ions which remain after emission of β rays then undergo further decomposition. The high energy β rays, on the other hand, are absorbed by the materials of the system containing the radioactive component, and their energy may be expended in the formation of additional ions and/or atoms and molecules of activated or high energy status, since the energy required to alter the extra-nuclear electron arrangement of a molecule is less than the energy of the emitted β rays.

From this knowledge of the β decay process, an observation of the types of compounds produced in gaseous systems as the end products of the decay of certain radioactive materials, and an observation of the reaction conditions obtaining in such systems, particularly the temperature coefficients involved in the formation of certain products, we postulated that free radicals are formed as intermediates in the reactions induced in the system by the absorption of the β rays. This was confirmed by the addition to the system of compounds which were capable of reacting with the free radicals so formed to produce stable compounds not readily undergoing further reaction. Since the addition of such radical-scavenging compounds

resulted in a substantial decrease in the rate of decomposition of the components of the system and in the rate of formation of decomposition products, the transitory existence of such free radicals was confirmed.

The effectiveness of the suppression of radiation damage and undesirable decomposition in gaseous systems as a result of the addition of suitable radical-scavenging compounds is demonstrated by the following examples:

EXAMPLE 1

Tritiated Propane-Propane System

The mechanism of the decomposition of tritiated propane gas while standing in a storage bulb can be divided into two categories:

Category (A): Direct decomposition due to the radioactive decay of the tritium atom with the emission of β rays.

The Category (A) decomposition process can be represented by mechanism reactions:

Category (B): Indirect decomposition due to ionizing radiation with β rays emitted in the direct decomposition of Category (A).

The Category (B) decomposition process can be represented by the mechanism equation:

When the tritiated propane is stored in the presence of propane as a diluent, an analogous equation may be used to represent the impingement of the β rays upon the propane molecule with resulting decomposition, thusly:

Obviously there is no way of preventing the spontaneous, direct decomposition of Category (A) from occurring. However, direct radioactive decay contributes negligibly to the over-all total decomposition in the system, the major role in the decomposition being played by the indirect decomposition resulting from molecular absorption of the high energy β rays (Category B). This becomes apparent when one considers that the average energy of electrons emitted in the β decay of tritium is 5.57×10^3 electron volts, and that it requires only 24 electron volts of energy to produce a C_3H_8^+ ion and an electron from the propane molecule. Since under most storage conditions nearly all of the β radiation energy is absorbed by the propane and tritiated propane molecules of the system, there therefore results more than two hundred C_3H_8^+ and $\text{C}_3\text{H}_7\text{T}^+$ ions which subsequently undergo decomposition or enter into the formation of new compounds. Thus, the Category (A) decomposition contributes, at most, 0.5 percent of the total decomposition.

The C_3H_8^+ and $\text{C}_3\text{H}_7\text{T}^+$ ions formed by the Category (B) mechanism then dissociate into free radicals. The free radicals so formed, as is well known, possess great chemical reactivity and many have such high energy content that they react upon collision with normal molecules, thereby forming a new and stable molecule of different structure and a new and different free radical, which again may react with a normal molecule and so on until eventually two active radicals collide and combine. The mechanism of decomposition and side product formation which is initiated in a propane=tritiated propane system by β

radiation (Category B) may thus be represented by the equations:

(Free Radicals of hydrogen and normally gaseous paraffins.)

We have found that the decomposition of the components of the propane-tritiated propane system may be inhibited, and the formation of side products suppressed by the introduction of a small amount of butadiene (normally gaseous diolefin) to the gaseous system. This compound reacts readily with methyl and ethyl free radicals to give high molecular weight, nongaseous products which can readily be removed from the storage bulb. It also reacts readily with the thermalized hydrogen atoms produced in the system. The amount of the scavenger which is to be added will, of course, depend upon the period of storage.

EXAMPLE 2

Tritium-Methane System

25 The mechanism of the radioactive decay of tritium may be expressed by the equation:

The β rays are then absorbed by the tritium and methane 30 of the system and the probable mechanism of the resulting reactions is:

35 The thermalized and "hot," or energetic, free radicals so formed then enter into sundry reactions by which several undesirable side products are formed, the most prevalent of which is tritiated methane.

To further establish the role of the β rays (as opposed 40 to the positive ions formed upon decay of the tritium) in the formation of the tritiated methane, a 156 cc. storage bulb containing purified tritium with traces of methane was subjected to gamma photon irradiation. The photon source was four spent fuel elements from the Materials

45 Testing Reactor, Arco, Idaho. The gaseous mixture was irradiated for eighteen hours at 4×10^5 roentgens/hour. A sharp increase in the initial rate of contamination of the system with tritiated methane was observed. Thus, it is estimated that practically all of the contamination 50 resulted from molecular absorption of β rays rather than from formation of products by reaction of the positive ion $(\text{He}^3\text{T})^+$ formed in the radioactive decay of the tritium.

To determine the effect of the addition of a suitable 55 radical-scavenging compound to the system, 10 mm. of mercury of nitric oxide gas was introduced into a 156 cc. storage bulb and then tritium gas containing a small amount of methane was introduced into the bulb. Under this condition, tritiated methane was not detectable in the bulb even after eighty hours of standing. Analysis of the system was made using a gas chromatographic instrument, modified by the addition of a 10 cc. ion chamber in series with the conductivity cell and a Vibrating Reed Electrometer. The accompanying drawing illustrates the

rate of tritiated methane formation in a system uninhibited with NO. In the graph, the ordinate values at the left are ratios of the areas under the tritiated methane peak to areas under the tritium peak divided by 10^{-5} . No curve is plotted to illustrate the formation of tritiated methane in the system inhibited with NO as described above, since, as has been said, none of the tritiated product was detectable under instrumental conditions even after eighty hours of standing. In each case, the bulbs which were utilized had previously been left in an annealing furnace for over forty-eight hours at 500° C. and de-

gassed for several hours by pumping in a high vacuum line.

The selection of NO as the scavenger to be used was, of course, in large part based upon its reactivity with the free radicals formed in the manner hereinbefore suggested. The NO, containing an odd number of electrons, combines instantly with neutral free radicals to produce normal nitroso compounds. Moreover, the bimolecular gas reaction between free methyl and nitric oxide proceeds easily at room temperature and has the low activation energy of nearly zero kilocalories. However, other scavenging compounds such as ethylene, propylene, butene, iodine and hydrogen iodide can all be utilized effectively. Since only the formation of compounds resulting from β radiation is suppressed by the addition of such free radical scavengers, labeling or tagging processes depending upon the reaction of dissociation products of the $(He^3T)^+$ ion with the compound to be tagged, such as the Wilzbach labeling process, are not interfered with by the scavenging compounds present in the tritium gas.

From the foregoing description, it will be perceived that the present invention provides a simple and effective method of inhibiting the detrimental effects of β radiation in systems containing radioactive materials emitting such particles in the process of radioactive decay. Such systems can, therefore, be stored over substantially longer periods of time without concern for the accelerated damaging of the radioactive material itself and the diluent which may be utilized in the system. The unsought labeling of organic impurities which may be present is also substantially eliminated.

As will be apparent to those skilled in the art upon reading the foregoing disclosure, many modifications, substitutions, and changes are possible in practicing the process of the present invention. Some of these have been suggested in the description set forth above, and such others as may fall within the scope of the appended claims are deemed to be within the spirit of the invention.

We claim:

1. The method of inhibiting molecular decomposition and undesirable chemical chain reactions in systems containing β ray emitting radioactive elements, and a compound capable of forming free radicals upon irradiation with beta photons, said compound being selected from the group consisting of hydrogen and normally gaseous paraffins which comprises introducing in said system a material selected from the group consisting of normally gaseous olefins, normally gaseous diolefins, NO, HI and I_2 which will freely react with free radicals formed in said system to produce stable compounds.

2. In a gaseous system including a compound containing at least one tritium atom, the method of inhibiting the formation of additional compounds as a result of radioactive decay of the tritium atom which comprises introducing to said system a radical-scavenging material selected from the group consisting of normally gaseous olefins, normally gaseous diolefins, NO, HI and I_2 which will readily react with free radicals resulting from decomposition of a compound selected from the group consisting of hydrogen and normally gaseous paraffins and produced by said decay to form stable compounds.

3. The method claimed in claim 2 wherein said radical-scavenging material is selected to yield nongaseous compounds upon reaction with said free radicals.

15 4. A method of inhibiting the formation of tritiated paraffin hydrocarbons in a gaseous system containing tritium and paraffin hydrocarbons which comprises introducing to said system as a radical-scavenging material nitric oxide which will react with free radicals resulting from radioactive decay of tritium atoms to produce stable compounds.

5. In a gaseous system containing tritium and traces of methane, the method of inhibiting the formation of tritiated methane which comprises adding to the system 25 an amount of nitric oxide sufficient to inhibit the formation of tritiated methane for the period of time desired.

6. In a gaseous system containing tritiated propane and propane, the method of inhibiting decomposition of the tritiated propane and propane, and the forming of undesirable products of such decomposition which comprises introducing to the system a radical-scavenging material selected from the group consisting of normally gaseous olefins, normally gaseous diolefins, NO, HI and I_2 which will readily form stable compounds with free radicals produced in the system as a result of radioactive decay of tritium atoms.

35 7. In a gaseous system containing tritiated propane and propane the method of inhibiting the formation of additional compounds during storage as a result of radioactive decay of tritium which comprises introducing into said system sufficient 1,3-butadiene to inhibit the formation of said additional compounds for the duration of the period of storage.
